WINTER CONTROL VALVE ARRANGEMENT IN
REFRIGERATING SYSTEM

Harry Robert Musson, Brantford, Ontario, Canada, assignor to Keeprite Products Limited, Brantford, Ontario, Canada

Application May 19, 1955, Serial No. 509,600

2 Claims. (Cl. 62—196)

This invention relates to refrigeration systems and more particularly to means to assure efficiency of systems or arrangements in which the condenser, particularly of the air-cooled type, is located out of doors and subject to low ambient temperatures as at geographical points where winters are severe.

A specific object of the invention is to prevent undesirable reduction in the pressure of the refrigerant at the expansion valve.

Another object of the invention is to reduce or prevent the formation of vapor in the pipe line between the receiver and the evaporator because of any undesirable reduction in pressure caused by too large cooling or radiating surfaces of the condenser exposed to low outside temperature.

Another object of the invention is to control the discharge or flow of refrigerant liquid from the condenser to receiver thus maintaining control over the amount of condensing surface in the condenser (being a function of the degree of flooding of the condenser).

These and other objects of this invention, and its advantages, will be apparent and may be better understood by referring to the following description of the preferred embodiment of the invention.

Referring now by numerals to the drawing, a compressor 10 of any conventional type has its discharge end connected by a conduit 11 to an air-cooled condenser 12. The discharge end of the condenser in turn is connected by conduit 13 with the inlet of a receiver 14. A conduit 15 between the conduits 11 and 13 serves to by-pass the condenser, being an equalizer line connecting the compressor discharge to the receiver inlet. Interposed in the length of the conduit 15 is a valve 16.

A conventional evaporator 17 is connected to the intake of the compressor as by a conduit 19. The discharge end of the receiver is connected to a conventional expansion valve 20 associated with the evaporator, as by a conduit 21.

Interposed in the length of the conduit 13 is a pressure-responsive valve 18, mechanically opening to allow the flow of liquid refrigerant from the condenser to the receiver or mechanically closing to stop the flow until the level of the liquid refrigerant rises in the condenser to the extent required for the proper rate of condensation required to maintain the predetermined minimum pressure necessary for proper operation.

Because the maintenance of this minimum pressure is of great importance, the function of this valve 18 is controlled by pressure-sensitive means depending on the

2

pressure at any convenient point of the system. For convenience and simplicity of installation, the pressure at the point where the valve 18 is located can be used for control purposes.

5 Pressure controlled valves are widely used and their design is common knowledge; therefore, no specific structure need be mentioned.

From the above disclosure, it will be seen that the refrigeration system as disclosed has special advantages in 10 use and operation and will provide safe and simple means to facilitate proper operation with air cooled condensers exposed to low ambient temperatures.

What I claim is:

1. In a refrigerating system including interconnected 15 compressor, condenser, receiver, expansion valve and evaporator wherein the condenser is of the air cooled type subject to low ambient temperatures, means for maintaining control over the amount of condensing surface in the condenser and the degree of flooding of the 20 condenser by controlling the flow of refrigerant liquid from the condenser to the receiver, said means comprising a liquid conduit from the condenser to the receiver and a pressure controlled valve in said conduit, said valve being responsive to a selected minimum pressure of the 25 refrigerant at the location of the valve to mechanically close and stop the flow of liquid refrigerant through said conduit until the level of liquid refrigerant rises in the condenser to reduce the effective cooling surfaces thereof, said valve being the only means in the entire system, 30 other than the expansion valve, for controlling the flooding of the condenser and varying the effective cooling surface thereof.

2. In a refrigerating system including interconnected 35 compressor, condenser, receiver, expansion valve and evaporator wherein the condenser is of the air cooled type subject to low ambient temperatures, means for maintaining control over the amount of condensing surface in the condenser and the degree of flooding of the condenser by controlling the flow of refrigerant liquid from the condenser to the receiver, said means comprising a liquid conduit from the condenser to the receiver and a pressure controlled valve in said conduit, said valve being responsive to a selected minimum pressure of the 40 refrigerant at the location of the valve to mechanically close and stop the flow of liquid refrigerant through said conduit until the level of liquid refrigerant rises in the condenser to reduce the effective cooling surfaces thereof, said valve being the only means in the entire system, other than the expansion valve, for controlling the flooding of the condenser and varying the effective cooling 45 surface thereof.

3. In a refrigerating system including interconnected 50 compressor, condenser, receiver, expansion valve and evaporator wherein the condenser is of the air cooled type subject to low ambient temperatures, means for maintaining control over the amount of condensing surface in the condenser and the degree of flooding of the condenser by controlling the flow of refrigerant liquid from the condenser to the receiver, said means comprising a liquid conduit from the condenser to the receiver and a pressure controlled valve in said conduit, said valve being responsive to a selected minimum pressure of the 55 refrigerant at the location of the valve to mechanically close and stop the flow of liquid refrigerant through said conduit until the level of liquid refrigerant rises in the condenser to reduce the effective cooling surfaces thereof, said valve being the only means in the entire system, other than the expansion valve, for controlling the flooding of the condenser and varying the effective cooling surface thereof, and said condenser being positioned above the receiver and said valve being located below the condenser and closely adjacent the receiver.
